UNITED STATES PATENT OFFICE.

HAROLD E. STURTEVANT, OF HARTFORD, CONNECTICUT, ASSIGNOR TO THE WHITNEY MFG. CO., OF HARTFORD, CONNECTICUT, A CORPORATION OF CONNECTICUT.

CHAIN AND PART THEREFOR.

Application filed October 25, 1923. Serial No. 670,636.

My invention relates to link chains of the silent type and consists of certain novel parts and combinations of parts to render the chain efficient, durable and noiseless in operation which novel parts and combinations will be specifically described herein and pointed out in the appended claims.

My invention will be better understood by reading the following description taken in connection with the drawings showing one embodiment thereof and in which Fig. 1 is a side view of a portion of a chain containing one embodiment of my invention; Fig. 2 is an inverted sectional view taken on the plane of the line II-II of Fig. 1; Fig. 3 is a side view of a single link; Fig. 4 is a sectional elevation on a scale larger than the preceding figures illustrating the positions assumed by the links of adjacent pitches and the pin passing through the openings therein on a straight run of the chain; Fig. 5 is a view similar to Fig. 4, illustrating the joint between the two pitches in the flexed position; Fig. 6 is a sectional elevation of a modification with the links of adjacent pitches in the positions assumed on a straight run of the chain; Fig. 7 is a view similar to Fig. 6 with the links of adjacent pitches flexed; Fig. 8 is a sectional elevation of a further modification showing the positions assumed by the links of adjacent pitches and the pin on a straight run of the chain; Fig. 9 is a view similar to Fig. 8 showing the positions of the links of adjacent pitches and that of the pin in the flexed position; Fig. 10 is a sectional elevation of a further modification showing the positions assumed by the links of adjacent pitches and the pin on a straight run of the chain; Fig. 11 is a view similar to Fig. 10, showing the links in the flexed position; Fig. 12 is a sectional elevation of a further modification illustrating the positions assumed by the links of adjacent pitches and the pin on a straight run of the chain and Fig. 13 is a view similar to Fig. 12 with the links of adjacent pitches flexed.

Referring to the embodiment shown in Figs. 1 to 5, the chain comprises a plurality of links 1 arranged side by side and a plurality of similar links 2 arranged side by side and overlapping the ends of the links 1. Each of the links 1 and 2 is provided at each end with a similar opening. From an inspection of Figs. 1 and 3, it will be noted

that the openings 3 in the ends of the links are at a slight angle to the vertical. This angle is approximately 8°, but may be made greater or less, if desired. The openings flare outwardly from the pivotal centers 4, 60 the sides 5 and 12, being curved. The side 5 is a segment of a circle with its center on a line 6 passing through the pivotal centers 4 and extending below and at an angle of about 8° to said center line 14 and the side 65 12 is a segment of a circle whose center is on the line 6 passing through the pivotal centers 4 and which line extends above and at an angle of about 8° to said center line 14. Therefore, the center line of the openings is at an angle of about 8° to a vertical line passing through the pivotal centers. 70

The ends 7 and 8 of the openings are concentric with the pivotal centers 4.

Pins 9 are placed through the registering 75 openings in the ends of the overlapping links 1 and 2. These pins are curved from edge to edge and have parallel surfaces. One of these surfaces, 13, is concave and the other is convex. In the straight run of the chain 80 the links 1 and 2 and pins 9 assume the positions shown in Fig. 4. From Fig. 4, it will be noted that the center line of the opening 3 in the link 1, and the center line of the opening 3 in the link 2 are at an angle of 85 about 16° to each other. The sides 5 of the links 1 engage the convex side of the pins 9 at points nearer the pivotal centers of the links than the points of engagement of the sides 5 of the openings in the links 2 on the 90 concave side of the pins. This causes the upper portion of the pins to engage the sides 12 of the links 1 at points x. As the joint is flexed from the position shown in Fig. 4 to that of Fig. 5, the surfaces 5 of 95 the links 2 move up and engage the pins 9 at points further away from the pivotal center of the pin than the points of engagement between the sides 5 of the links 1 and the pins. This causes the pins to touch the sides 100 12 of the links 1 at points Y. The fact that the points of engagement between the links of adjacent pitches and the pins are not in a line parallel to the center line of the chain, but in a line at an angle thereto, creates a 105 resultant of force which tends to take the curvature out of the pins. This arrangement, therefore, adds a slight resiliency to the joint and has a tendency to reduce the noise of the chain, but is not sufficient to 110

permit the chain to substantially increase in length under load.

Sufficient clearance exists between the edges 10 and 11 of the pins 9 and the links 6 so as to relieve any excess friction that might otherwise develop at these points. The ends 7 and 8 of the openings are concentric with the pivotal centers 4 and the pins 9 stand in the position shown in Figs. 1 to 4 in the straight run of the chain and as shown in Fig. 5 when the chain is flexed. That is to say, the pins are slightly tilted as above explained.

As the links of adjacent pitches move 15 relative to each other from the positions shown in Fig. 4, to those shown in Fig. 5, the sides 5 of the links 1 and 2 rock upwardly on the sides of the pins from the positions shown in Fig. 4 to those shown in Fig. 5. This rocking movement of the links on the flat faces of the pins is accomplished with a minimum friction and noise with the resultant minimum of wear and maximum efficiency.

25 The opposite sides 12 of the openings of the links of adjacent pitches do not engage the pins when the chain is under tension and, therefore, do not take any active part in the operation of the chain.

30 The pins 9 are generally rectangular in cross section with the edges 10 and 11 rounded. These pins are preferably made by rolling rods to the cross section shown. By the use of pins of simple cross section, 35 the same may be manufactured inexpensively and the cost of the chain thereby reduced. The pins shown in this application may be made from what is termed stock material.

40 In the arrangement shown in Figs. 6 and 7, the pins are each divided into two parts A and B. The corresponding parts of this structure are numbered the same as in Figs. 4 and 5 but have the exponent "a" applied thereto. In the construction shown in Figs. 6 and 7, the thickness of the pin as a whole in the center line of the chain is greater than in the form shown in Figs. 4 and 5. Since the two contacting flat faces 45 of the two members A and B of the pin are not perfect planes but are necessarily slightly irregular, there will be a small amount of elasticity in the joint of the form shown in Figs. 6 and 7. The resiliency or elasticity has the effect of reducing the noise of the chain. If desired, the two members A and B may be made into a single piece.

45 In the modification shown in Figs. 8 and 9, the pins are composed of two members A and B, the member A being curved and the member B being straight. Otherwise, this modification is similar to that shown in Figs. 6 and 7 and corresponding parts 50 are similarly indicated, but have the expo-

nent "b" applied thereto. By the arrangement shown in Figs. 8 and 9, the member A has a rolling contact on the member B so that when the joint is flexed the parts move from the positions shown in Fig. 8 70 to the positions shown in Fig. 9; that is to say, the sides 5^b of the links 1 roll upwardly on the members B and the members A roll upwardly on the members B at the same time the sides 5^b roll upwardly 75 on the concave sides of the members A. There are, therefore, three sets of rolling contacts in this modification which have the effect of reducing the friction of the joint and thereby rendering the chain 80 more efficient. The fact that the member A is slightly curved also adds resiliency to the joint which has the effect of reducing the noise.

In Figs. 10 and 11 is shown a modification similar to that shown in Figs. 8 and 9 except that both the members A and B are curved. The members A have a slightly greater curvature than the members B. These members are so placed that the convex sides of the members A engage the concave sides of the members B. The sides 5^c of the links 1 engage the convex surfaces of the members B and the sides D of the links 2 engage the concave sides of 95 the members A. This modification like that shown in Figs. 8 and 9 has three sets of rolling contacts and the curvature of the members A and B adds slightly to the resiliency of the joint. 100

In Figs. 12 and 13, I have shown a form of joint which, in many respects, is preferable to any of the joints shown in this application. In this form of the invention, the pin 9^d is straight from edge to edge 105 and is made of a single piece of metal and is, therefore, very simple in structure and easy to manufacture. The pin may be made by rolling the same from a metal rod of suitable cross section. The action of the 110 links on this pin is identical with that form shown in Figs. 6 and 7. The chief difference between these two modifications is that the pins in Figs. 12 and 13 are made of a single piece, whereas in Figs. 6 115 and 7 two similar pieces are used.

The side walls of the opening in this modification are the same as those shown and hereinafter described. In this form I have shown links 6^d and 15 intersecting 120 at the pivotal centers 4^d. The side walls of the opening in the link 1 have their centers on the link 6^d and the side walls of the opening in link 2 have their centers on the link 15. The links 6^d and 15 are 125 at an angle of about 16° to each other. Each of these links is at an angle of approximately 8° to the center line 14 of the link.

I wish to call attention to the fact that in 130

all of the modifications shown and described the opposing contacting surfaces 5 of the links on the pins travel upward on the pins as the joints are flexed. In each instance 5 shown these points are below the center line of the chain during the straight run of the chain as shown in Figs. 4, 6, 8, 10 and 12, whereas, they are above the center line of the chain when the joints are flexed as shown 10 in Figs. 5, 7, 9, 11 and 13.

Chains which I have constructed like each of the modifications shown have upon test shown that they do not "chew up" the sprocket wheels as do certain other chains 15 constructed along other lines and from which the feature above described is absent. It is, therefore, my present belief that the "chewing up" action is avoided by so arranging the joints that the opposing contact 20 surfaces of links of adjacent pitches may move from below the center line of the chain to above the said center line as the joints are flexed around the sprockets.

From the foregoing, it will be seen that in 25 all the forms shown pins are used which may be easily and inexpensively manufactured from stock material. One or more members made from such material may be used as a pin, depending upon the circumstances under 30 which the particular chain is to be used. Rolling contacts are provided in each case thereby reducing the friction to a minimum and increasing the efficiency and life of the chain. In some instances, the resiliency has 35 been imparted to the joint by bending or otherwise arranging one or both of the members constituting the pin thereby lessening the noise usually present in chains of this type. The openings of the links are so 40 formed that the links are interchangeable, thereby greatly lessening the manufacturing cost and facilitating the automatic assembly of the links in the chains.

It will be noted from Figs. 1 and 2 that 45 the ends of the pins 9 are riveted over adjacent the outside links 1 and that no washers are placed between the ends of the pins and the links. This simplifies the structure of the chain and also lessens the cost of manufacture without, in any manner, decreasing 50 the efficiency of the chain.

Slight changes may be made in details without departing from the spirit of my invention.

I claim:

1. A chain of the silent link type having joints comprising links with registering openings and two pin members in said openings, said members having parallel sides and the side walls of said openings being curved and having rocking contact with said pin members.

2. A chain of the silent link type having joints comprising links having registering openings flaring from the pivotal centers, the side walls of said openings being curved, two pin members in said openings, said members having adjacent parallel sides and so arranged that the side walls of said openings form rocking contact with the other sides of said members.

3. A chain of the silent link type having joints comprising links having registering openings flaring from the pivotal centers, the side walls of said openings being curved, two pin members in said openings each having a substantially rectangular cross section and arranged side by side, the side walls of said openings engaging said pin members to form rocking joints therewith.

4. A chain of the silent link type having joints comprising links having registering openings flaring from the pivotal centers, the side walls of said openings being curved, a plurality of pin members placed side by side and having parallel contacting surfaces, the side walls of the link openings engaging the outside surfaces of said members and forming rocking contact therewith.

5. A chain of the silent link type having joints comprising links having registering openings flaring from the pivotal centers, the side walls of said openings being curved, a plurality of similar pin members placed edgewise in said openings and the side walls of said openings forming rocking contacts with said members.

6. A pin for silent link chains comprising a plurality of members substantially rectangular in cross section.

HAROLD E. STURTEVANT.
